GUARD FOR GUY RODS AND CABLES

Filed June 25, 1928

INVENTOR
JAMES W. SHOPE.
BY *Martin P. Smith*,
ATTORNEY.

UNITED STATES PATENT OFFICE

JAMES W. SHOPE, OF SOUTH GATE, CALIFORNIA, ASSIGNOR TO WESTERN ELECTRIC COMPANY, INCORPORATED, A CORPORATION OF NEW YORK

GUARD FOR GUY RODS AND CABLES

Application filed June 25, 1928. Serial No. 288,077.

My invention relates to a guard or shield for the anchor rods and cables that are used as guys for poles carrying overhead wires and cables, and the principal object of my invention is to provide a guard or shield that is relatively simple in construction, inexpensive of manufacture, and which is provided with fastening means that engages an anchor rod and cable, thereby enabling the guard or shield to be readily secured in position upon the guy without the necessity for extraneous fastening means such as bolts, clamps and the like.

Further objects of my invention are to provide a guard for guy rods and cables that will meet State laws and city ordinances relating to the equipping of guy ropes and cables with guards, shields and the like for the protection of pedestrians, and further to provide a guard of the character referred to that will be effective in saving much of the time, labor and consequent expense that is now involved in the applying of guards or shields to guy ropes and cables.

With the foregoing and other objects in view, my invention consists in certain novel features of construction and arrangements of parts that will hereinafter be more fully described and claimed and illustrated in the accompanying drawing, in which:

Fig. 1 is a side elevational view of a guard constructed in accordance with my invention and the same being shown in proper position upon a guy rod and cable.

Fig. 2 is a front elevational view of the shield.

Fig. 3 is a rear elevational view of the shield.

Fig. 4 is a vertical longitudinal section taken through the center of a shield of my improved construction, the same being shown in position upon a guy and with parts of the shield broken away.

Fig. 5 is a view looking against the underside of the shield with parts thereof broken away.

Fig. 6 is an enlarged cross section taken on the line 6—6 of Fig. 4.

Fig. 7 is an enlarged cross section taken on the line 7—7 of Fig. 4.

Referring by numerals to the accompanying drawing which illustrates a practical embodiment of my invention, 10 designates the body of the shield which is preferably formed of suitable sheet metal that is bent to form an inverted channel so that said body is substantially semi-circular in cross section and the over-all length thereof being approximately eight or nine feet in order to meet the requirements of city laws and State ordinances relative to guards for guy rods and cables.

Secured to the under faces of one end of the inverted channel-shaped body 10 in any suitable manner, preferably by means of rivets 11, is a longitudinally disposed strap 12, the outer end of which projects a short distance beyond the corresponding end of the body 10, and said projecting end is formed into a depending U-shaped hook 13 of such size as to receive the anchor rod to which a guy wire or cable is connected.

The opposite or inner end of the strap 12 is bent downwardly so as to occupy a plane substantially at right angles to the plane occupied by the strap 12, thereby forming a finger or prong 14 which, when the guard is applied for use, projects through the eye E that is formed on the upper end of the guy anchor rod R, or said prong or finger may pass through the loop L that is formed at the lower end of the cable C, and which loop passes through the eye E of the anchor rod.

The end of the cable C beyond the loop L is secured to the body of said cable in any suitable manner, preferably by means of a three-bolt clamp as illustrated in Fig. 4.

Secured to the underside of the upper end of the body 10 is a longitudinally disposed strap 15, the outer portion of which projects a short distance beyond the corresponding end of said body, and said projecting portion being bent to form a depending U-shaped hook 16 that is adapted to receive the guy cable C.

The hooks 13 and 16 at the ends of the guard are oppositely arranged relative to each other. In other words the hook 13 at the lower end of the guard projects laterally in one direction while the hook 16 at the up-

per end of said guard projects laterally in the opposite direction.

Formed integral with the lower or inner end of the strap 15 and arranged transversely on the underside of the body 10 is a rib 17 that functions as a bearing or saddle for the cable C when the guard is positioned on the guy.

It will be understood that practically all 10 guys have poles carrying overhead wires and cables including an anchor rod that projects ten or twelve inches above the surface of the ground and the upper end of said rod being provided with an eye that receives the loop of 15 the guy cable.

My improved guard is intended to be applied over the lower portion of the guy and to extend from a point near the ground upwardly on said guy approximately eight or 20 nine feet, thus complying with legal requirements.

In the application of my improved guard 25 the hook 13 at the lower end of the guard is engaged beneath the anchor rod R a short distance above the point where the same emerges from the ground and the guard is now forced downwardly toward the guy and manipulated so that the finger or prong 14 passes through the eye E at the upper end of 30 the anchor rod, or if said eye is turned into a substantially vertical position so that the loop L at the lower end of the cable occupies a substantially horizontal position, then the finger or prong is forced through said loop 35 just below the lower end of the clamp that connects the end of the cable to the body thereof and the engagement of this prong or finger in the eye or loop anchors the guard against any longitudinal movement of the 40 guy.

The upper portion of the guard is pressed against the cable C so that the latter bears against the saddle 17 and by applying downward pressure to the extreme upper end of 45 the guard and the hook 16 that projects therefrom the said hook is engaged beneath the cable and the resiliency of said cable, and particularly those portions engaged by the saddle 17 and hook 16, tends to produce a 50 clamping effect so that the guard is effectually secured in proper position to the guy.

Thus when properly applied to the lower portion of the guy my improved device forms a guard or shield that extends for a substantial distance upwardly from the ground in 55 which the guy is anchored, and thus said guard or shield provides a readily visible member that will be effective in minimizing accidents resulting from contact between 60 pedestrians and the lower portion of the guy.

An especially desirable feature of my invention is the absence of extraneous means for securing the guard in position upon the guy, for by providing the hooks at the ends 65 of the guard and the depending prong or

finger the guard may be very easily or quickly applied to the guy without resorting to the use of bolts, clamps or the like, and thus much time, labor and consequent expense are saved through the use of the improved guard.

It will be readily understood that minor changes in the size, form and construction of the various parts of my improved guard for guy rods and cables may be made and substituted for those herein shown and described without departing from the spirit of my invention, the scope of which is set forth in the appended claims.

I claim as my invention:

1. A guard for guy rods and cables comprising a channel-shaped member adapted to overlie a portion of the guy, and substantially U-shaped guy engaging hooks carried by and projecting from the ends of said guard which hooks are arranged substantially at right angles to the axis of the channel shaped member.

2. A guard for guy rods and cables comprising a channel-shaped member adapted to overlie a portion of the guy, guy engaging hooks carried by and projecting from the ends of said guard, and a prong depending from the underside of said guard adjacent to one end thereof.

3. A guard for guy rods and cables comprising a channel-shaped member adapted to overlie a portion of the guy, guy engaging hooks carried by and projecting from the ends of said guard, and a guy engaging saddle arranged on the underside of said channel-shaped member.

4. A guard for guy rods and cables comprising a channel-shaped member adapted to overlie a portion of the guy, means secured to said guard for securing the same to a guy, a guy engaging prong depending from the underside of said guard, and a guy engaging saddle arranged on the underside of said guard.

5. A guard for guy rods and cables comprising a channel-shaped member adapted to overlie a portion of the guy, substantially U-shaped guy engaging hooks carried by and downwardly projecting from the ends of said guard, and guy engaging members depending from the underside of said guard intermediate its ends.

6. A guard for guy rods and cables comprising a channel-shaped member adapted to overlie a portion of the guy, and oppositely arranged hooks secured to and projecting from the ends of said guard.

7. A guard for guy rods and cables comprising a channel-shaped member adapted to overlie a portion of the guy, oppositely arranged hooks secured to and projecting from the ends of said guard, and guy engaging members depending from the underside of said guard between said hooks.

8. The combination with a guy anchor rod

having a loop and a guy line connected to said loop, of an inverted channel shaped member adapted to overlie a portion of said guy rod and guy line and a prong carried by said member and projecting through the loop on said guy rod.

9. The combination with a guy anchor rod having a loop and a guy line connected to said loop, of an inverted channel shaped member adapted to overlie a portion of said guy rod and guy line, a prong carried by said member and projecting through the loop on said guy rod and hooks on the ends of said member for engaging said guy rod and guy line.

10. The combination with a guy, of an inverted channel shaped guard adapted to overlie a portion of the guy and means carried by said guard for engaging said guy and adapted, through the resiliency of the guy to anchor the guard thereto.

11. A device of the class described, comprising, an elongated body, a hook at the lower end of said body for attachment of the body to the object to be protected adjacent the ground line, and means for securing the upper end of said body to the object to be protected.

12. A device of the class described, comprising, an elongated body, said body open at one side along its length, a hook at the lower end of said body and disposed inwardly relative thereto for attachment of the body to a guy wire, with the lower end of the body disposed adjacent to the ground line, and means for securing the upper end of the body to the wire.

13. In a device of the class described for protecting a guy wire, an elongated body, a flange disposed outwardly from the underside of the lower end of the body, a hook disposed outwardly from the underside of the extreme lower end of said body, said hook facing the edge of said flange, whereby the body may be secured on the guy wire with the lower end of the body adjacent the ground line, and means for attaching the upper end of said body to the guy wire.

14. In combination, a guy rod, a guy wire secured thereto, an elongated trough-shaped member lying along said guy rod and said guy wire and fastened thereto, and a projection at the lower end of said guard which when the guard is forced against the wire, grips said guy rod, thereby holding the lower end of the guard firmly in place.

In testimony whereof I affix my signature.
JAMES W. SHOPE.
